UNITED STATES PATENT OFFICE.

LEO F. ADT, OF ALBANY, NEW YORK.

EYEGLASS-MOUNTING.

1,040,101.

Specification of Letters Patent.

Patented Oct. 1, 1912.

Application filed May 13, 1910. Serial No. 561,167.

To all whom it may concern:

Be it known that I, LEO F. ADT, of Albany, in the county of Albany and State of New York, have invented certain new and useful Improvements in Eyeglass-Mountings; and I do hereby declare the following to be a full, clear, and exact description of the same, reference being had to the accompanying drawings, forming a part of this specification, and to the reference-numerals marked thereon.

The present invention relates to eyeglass mountings and more particularly to that type in which the nose guards are moved toward the nose under the action of springs, and away from the nose by means of operating portions, such as finger pieces arranged at the front of the mounting, and it has for an object to provide a construction in which springs of maximum strength are secured without rendering the mounting conspicuous.

To these and other ends the invention consists in certain improvements and combinations of parts all as will be hereinafter more fully described, the novel features being pointed out in the claims at the end of the specification.

In the drawings: Figure 1 is a front view 30 of a mounting embodying the present improvements, with one of the guards and its operating spring removed; Fig. 2 is a bottom view of a portion of the mounting in proximity to one of the guards, the nose bearing member of the guard being removed for the purpose of clearness; Fig. 3 is a top view of the same mounting in proximity to one of the guards; Fig. 4 is a sectional view 35 on the line *a—a* of Fig. 2; Fig. 5 is a horizontal section on the line *b—b* of Fig. 4; Fig. 6 is a top view of a portion of another mounting constructed in accordance with the present invention, Fig. 7 is a horizontal section of the mounting shown in Fig. 6, 40 and Fig. 8 is a section on line *c—c* of Fig. 6.

In the embodiment of the invention illustrated in Figs. 1 to 5, the support for the lenses A embodies an arched or bridging portion 1, and lens attaching devices 2, preferably in the form of the usual ears co-operating with opposite faces of the lenses, the bridging portion being in this instance connected to the lens attaching devices by horizontal portions, each of which preferably 50 projects forwardly of an extremity of the bridging portion and is formed by horizon-

tal walls or members 3 and 4 spaced from each other and connected at their outer sides by the proximate lens attaching device, and on their inner sides by a portion 5 forming a continuation of the bridging portion to bear against the nose of a wearer. In this instance, the pockets open horizontally at the front and the rear of the mounting and receive the springs for positioning the guards, as will be hereinafter more fully set forth. The guards may be in the form of levers 6, each mounted to swing on the support and preferably on one side, in this instance, the upper side, of the horizontal connecting portion between the bridging portion 1 and a lens attaching device. The guards may carry permanent and depending pivot pins 7 which may turn in the members 3 and 4 in advance of the extremities 55 of the bridging portion. In front of the mounting each guard lever 6 is provided with a finger piece 8 bent vertically or downwardly so as to hide the opening in the front of the connecting portion. At its rear end said guard may carry a nose engaging member having an upper pad 9 and a lower pad 10. To the end of positioning the guards, each is controlled by a spring 60 preferably in the form of a coil 11 of flat volute formation arranged in one of the pockets about a vertical axis to one side of the axis of turning of its guard, in this instance the rear side. An arm 12 may be 65 extended forwardly from the spring and interlocked with a recessed portion 13 in the inner vertical edge of the finger piece 8, thus preventing the separation of the guard from the support. With the object in view of securing each spring within its pocket one 70 of the walls of the latter, in this instance the bottom wall 4, may be provided with a slot or groove 14 opening at the rear of the mounting and adapted to receive a depending projection 15 on the inner end of the coil, thus maintaining said end against 75 turning, while, at the same time, permitting the detachment of the spring from the mounting when the forward end of the arm 12 is disengaged from the finger piece 8. 80 It is apparent that with this embodiment when the finger pieces 8 are pressed toward each other the nose bearing portions of the guards will be separated and that when the pieces are released the nose bearing portions 85 will be moved toward each other under the action of their springs. Separate fastening 90

110

devices for the guards and the springs are not required as the springs interlock with the support and engage the guards in such a manner that the latter are retained in position on the support. The pocketed portions project forwardly from the bridging portion and thus permit the mounting to give a "saddle bridge" effect with some of the resulting advantages of the latter.

- 10 In the embodiment of the invention illustrated in Figs. 6 and 7, the walls 3^a, 4^a of each connecting portion form a pocket between them and the connection 5^a closes the pocket, except at the front. The pivots of 15 the guards are in the form of rigid headed projections 7^a on the upper side of each wall 3^a, the guard levers 6 having laterally opening bearings 7^b held in engagement with the pivots by the guard positioning springs. 20 The latter in this embodiment are in the form of coil springs 11^a of flat stock and volute form arranged in the pockets with their axes in rear of the turning axes of the guards, arms 12^a being extended forwardly 25 therefrom to coöperate with the inner edges of the downwardly turned finger pieces 8. A feature of the springs of this construction is the novel interlocking connection with the mounting. This is secured by providing the inner end of each spring with a forwardly extending arm 15^a which is notched at 15^b and coöperates with a vertical rib or projection 15 on the inner side of the pocket at the front of the latter. This 30 connection is sufficient to hold each spring in its pocket and the latter confines and supports the spring in other directions. 35 In both embodiments, the nose engaging portions of the guard are separated by moving the finger pieces 8 toward each other and when the latter are released the springs move the guard in the other direction. The upper and the lower walls of the pockets are connected on their inner and their outer 40 sides so that one connection of the bridging portion with the lenses is strengthened while the walls may be made of thinner material. The springs for the guards are so arranged in the pockets that arms of 45 greater length may be obtained without rendering the mounting conspicuous. The pockets have their greatest length transverse to the plane of the lenses thus giving the guard levers greater bearing surfaces on 50 their under sides and reducing the looseness in the mounting.

I claim as my invention:

1. In an eyeglass mounting, the combination with a support for the lenses comprising a pair of members providing a pocket between them, of a nose guard mounted to swing on one side of said members, and a coil spring arranged between the members about an axis to one side of the turning 55 axis of the guard and having an arm en-

gaging the guard on the other side of its turning axis.

2. The combination with a support for the lenses comprising a pair of members providing a pocket between them, of a nose guard mounted to swing to one side of said members, and a coil spring arranged between said members about an axis in rear of the turning axis of the guard and having an arm extending forwardly and connected to the lever in front of the turning axis of the latter.

3. In an eyeglass mounting, the combination with a support for the lenses comprising a pair of members providing a pocket between them, of a nose guard mounted to swing on the upper side of said members, and a coil spring arranged between said members about an axis in rear of the turning axis of the guard and having an arm extending forwardly and coöperating with the guard in front of the turning axis.

4. In an eyeglass mounting, the combination with a support for the lenses having a pair of spaced members thereon connected together on their inner and their outer sides, and providing a pocket opening horizontally, of a nose guard mounted to swing on one side of the pair of members, and a spring mounted between the members and having an arm extending through the opening and connected to the guard.

5. The combination with a support for the lenses comprising a bridging portion, a lens attaching device and a pair of members connected to the lens attaching device and to the bridging portion and providing a pocket between them opening horizontally, of a nose guard swinging on one side of the spaced members, and a spring arranged between the members and connected to the guard through the opening.

6. In an eyeglass mounting, the combination with a support for the lenses comprising a bridging portion, a lens attaching device and a pair of spaced horizontally arranged walls connected on their inner sides to the bridging portion and on their outer sides to the lens attaching device, of a spring arranged between said walls, and a nose guard mounted to swing on the support and having the spring connected thereto.

7. In an eyeglass mounting, the combination with a support for the lenses comprising a bridging portion, a lens attaching device, and a pair of spaced horizontally arranged walls connected on their inner sides to the bridging portion and on their outer sides to the lens attaching device forming a pocket between them, the latter having an opening in one side, of a guard mounted to swing on the support, and a spring mounted in the pocket and having an arm extending through the opening and connected to the guard.

8. In an eyeglass mounting, the combination with a support for the lenses comprising a bridging portion, a lens attaching device and a pair of spaced horizontally arranged walls connected on their inner sides to the bridging portion and on their outer sides to the lens attaching device to form a pocket between them, said pocket having its front wall open, of a nose guard mounted to swing on the outside of one of said walls and having a portion bent to lie in front of the opening in the pocket, and a spring mounted in the pocket and having an arm extending through the opening with connection with the guard. 15
9. In an eyeglass mounting, the combination with a support for the lenses comprising a bridging portion, a lens attaching device, and a pair of spaced horizontally arranged walls connected on their inner sides with the bridging portion and on their outer sides with the lens attaching device to provide a pocket between them, the front wall of said pocket being open, of a nose guard mounted to swing on the upper surface of the top wall and having a portion depending in front of the pocket, and a spring mounted in the pocket and having an arm extending forwardly and connected to the guard. 20
10. In an eyeglass mounting, the combination with a bridging portion and a lens attaching device, of a member connecting the lens attaching device to the bridging portion and extending forwardly from the end of the bridging portion, a nose guard pivoted to the connecting member forward of the extremity of the bridging portion and a spring for positioning the guard coiled in rear of the pivot thereof. 25
11. In an eyeglass mounting, the combination with a bridging portion and a lens attaching device, of a pocketed connection between the attaching device and the bridging portion projecting forwardly of the proximate extremity of the bridging portion, a nose guard pivoted to the pocketed connection in advance of the extremity of the bridging portion, and a spring for the guard coiled within the pocketed portion in rear of the pivot of the guard and connected to the latter. 30
12. In an eyeglass mounting, the combination with a bridging portion and a lens attaching device, of a pocketed connection between them opening at the front of the mounting and projecting forwardly of the proximate end of the bridging portion, a nose guard pivoted to the pocketed portion in advance of the extremity of the bridging portion, and a coil spring for the guard mounted in the pocketed portion about an axis in rear of the turning axis of the guard and having a forwardly extending spring extending through the opening in the pocket and connecting with the guard in front of the turning axis of the latter. 35
